(57) **CLAIM**

The ornamental design for a wireless control device, as shown and described.

DESCRIPTION

1. Wireless control device

1.1 : Perspective

1.2 : Perspective

1.3 : Front

1.4 : Back

1.5 : Left

1.6 : Right

1.7 : Top

1.8 : Bottom

1.9 : Enlarged

The broken lines depict portions of the wireless control device that form no part of the claimed design. Reproduction 1.9 is an enlarged view of a portion labeled "9" in reproduction 1.2. The dash-dot-dash lines in the reproductions and the number "9" in reproduction 1.2 are for the purpose of depicting the cut line of the enlarged view that form no part of the claimed design.
